EXTRACTOR DEVICE FOR PIPE CLEANERS

Charles Wilfred Hewitt, Heswall, England

Application February 4, 1949, Serial No. 74,569
In Great Britain December 20, 1948

11 Claims. (Cl. 131—245)

1

This invention relates to a device for use in cleaning tobacco pipes and more particularly for use in connection with the removal, by pulling it through the bowl, of an ordinary wire-wool pipe cleaner inserted through the mouth-piece for the purpose of cleaning a tobacco pipe.

It is an object of the invention to provide an effective rigid device for the purpose described which can be made from wire, the cost in relation to the cost of a cleaner being so small that it is commercially practicable to discard the extractor device with the fouled cleaner.

I have found that an extractor device of the type above described can be made from a length of substantially rigid wire double cranked at one end to form a substantially V-shaped hook in the longitudinal plane of the main stem of wire, the outer arm, that is, the arm remote from the stem of wire, extending beyond the inner arm in the direction of the length of the arm. It is essential for the device to function that certain dimensions fall within critical ranges. Thus the wire should be of a thickness, in the case of wire of circular cross-section, equivalent to at least 0.032 inch, the angle between the arms or limbs of the V-shaped hook should be within the range 7 to 20° and the inner radius of curvature at the elbow between the two arms should be less than 0.032 inch.

Preferably the end of the wire stem remote from the hook is shaped to form a gripping means for the device which means lie in the plane formed by the stem and the bent arms of the hook.

Whilst the divergence or taper between the two arms may be spread between the two arms, that is, both arms being disposed at an angle slightly greater than a right angle to the stem but in opposite directions or the inner arm greater and the outer arm less than a right angle from the stem so that the acute angle therebetween is bisected by a line at right angles to the stem, it has been found that to ensure optimum efficiency of the device in operation, the taper should be located solely in the inner arm, that is, the arm adjacent to the stem of the device should be disposed at an obtuse angle slightly greater than a right angle to said stem, the other or outer arm being disposed in a direction at right angles to the stem of the device. The degree of divergence or taper should preferably be 12° but some tolerance in either direction will permit reasonably efficient operation of the device.

The wire employed in the construction of the

device should be substantially rigid, that is, the rigidity should be such that the arms do not collapse or open out when the device is pulled in order to remove the cleaner it is gripping from the pipe bowl. In this connection it has been found that with a wire of circular cross-section the thickness should be at least 0.032 inch. The material must also, of course, be of a stiffness which will not cause the arms to collapse. Copper wire, for example, would not be suitable and with the cost factor in mind an unannealed mild steel wire is preferably employed.

The inner radius of curvature of the elbow between the arms should be, as stated, less than 0.032 inch and preferably is 0.02 inch. As already indicated, the outer arm must overhang or extend beyond the inner arm in a direction transverse to that of the main stem. It has been found that the amount of overhang should not be more than 0.05 inch, the preferred range being 0.05 to 0.02 inch. The distance from the inner part of the elbow to the lower part of the main stem may vary between 0.15 and 0.20 inch. If this dimension varies to any substantial extent from the aforementioned range it renders operation of the device very uncertain.

One embodiment of the device in accordance with the invention will now be described, by way of example, with reference to the accompanying drawings in which

Figure 1 is a view in longitudinal elevation of one embodiment of a device in accordance with the invention,

Figure 2 is a cross-section along the lines II—II of Figure 1, and

Figure 3 is a view in longitudinal elevation of an embodiment in which taper is spread between both arms.

The device consists of a length of mild steel wire having a diameter of 0.04 inch. At one end it is double cranked to form divergent arms 11 and 12, one of which, the remote arm 12, is at right angles to the main stem 13, the other arm 11, that is, the inner arm, extending at an obtuse angle slightly greater than a right angle from the main stem the angle of divergence between the two arms being 12°. The inner radius of curvature r at the elbow 10 between the two arms is 0.02 inch. The overhang of the outer arm, that is, the length x is 0.05 inch and the distance y is 0.20 inch. The end of the device remote from the divergent arms is bent into circular form 14, to provide means for gripping the device between the fingers. The diameter of

this circle which is in the same plane as that of the hook is seven sixteenths of an inch. In the case of the device shown in Figure 1, a suitable length for the main stem would be 1.4 inches and the inner radius of curvature between the inner arm and main stem would be approximately 0.06 inch. Instead of being formed as a more or less complete circle as shown in Figure 1, the end of the wire can be extended to overlap as indicated at 14a in Figure 3.

In Figure 3 is shown a modification in which both inner and outer arms are divergent. The inner radius of curvature will be 0.02 inch, whilst the inner and outer arms are disposed at an angle of 6° to a line passing transversely through the elbow 10 and at right angles to the stem.

To remove an ordinary "wire-wool" pipe cleaner which has been inserted in the mouthpiece of a pipe and pushed through until a portion extends into the bowl of the pipe, the device above described is operated as follows:

The extractor device is inserted into the bowl with the hook lying alongside the projecting portion of the pipe cleaner. The device is then twisted until the hook is substantially at right angles to the pipe cleaner whereupon the action of withdrawing the extractor device causes it to grip the cleaner and the continued withdrawing action pulls the cleaner through the stem and out of the bowl. Both cleaner and extractor device may then be thrown away.

It will be appreciated that the cost of devices in accordance with this invention will be relatively small even in relation to an ordinary "wire-wool" pipe cleaner and that such devices can be equally expendable with the wire pipe cleaners without materially altering the economics of manufacture and purchase of cleaner and cleaner extractor device.

I claim:

1. A device for use in connection with the removal of an ordinary wire-wool pipe cleaner from a tobacco pipe which device consists of a length of substantially rigid wire of a minimum thickness equivalent to at least 0.032 inch, double cranked at one end to form a substantially V-shaped hook in the longitudinal plane of the main stem of wire, the angle between the arms of the V-shaped hook being within the range 7 to 20°, the inner radius of curvature at the elbow between the two arms being less than 0.032 inch, the arm remote from the stem of wire extending beyond the inner arm in the direction of the length of the arms.

2. A device for use in connection with the removal of an ordinary wire-wool pipe cleaner from a tobacco pipe which device consists of a length of substantially rigid wire of a stiffness similar to unannealed steel wire of a minimum thickness equivalent to at least 0.032 inch, double cranked at one end to form a substantially V-shaped hook in the longitudinal plane of the main stem of wire, the other end being shaped to form a gripping means for the device which gripping means lie in the common plane of the stem and the V-shaped hook, the angle between the arms of the V-shaped hook being within the range 7 to 20°, the inner radius of curvature at the elbow between the two arms being less than 0.032 inch, the arm remote from the stem of wire being straight and extending beyond the inner arm and stem in the direction of the length of the arms.

3. A device for use in connection with the

removal of an ordinary wire-wool pipe cleaner from a tobacco pipe which device consists of a length of substantially rigid wire of a hardness and stiffness similar to unannealed mild steel of a minimum thickness equivalent to at least 0.032 inch, double cranked at one end to form a substantially V-shaped hook in the longitudinal plane of the main stem of wire, the arm of said hook adjacent the stem being bent outwardly

5 and disposed at an angle slightly greater than a right angle to the stem, the outer arm being bent back in the plane of the first arm and stem and disposed substantially at right angles to the stem, the angle between the arms of the V-shaped hook being within the range 7 to 20°, the inner radius of curvature at the elbow between the two arms being less than 0.032 inch, the arm remote from the stem of wire extending beyond the inner arm and stem in the direction of the length of the arms.

10 4. A device for use in connection with the removal of an ordinary wire-wool pipe cleaner from a tobacco pipe which device consists of a length of substantially rigid wire of a minimum thickness equivalent to at least 0.032 inch, double cranked at one end to form a substantially V-shaped hook in the longitudinal plane of the main stem of wire, the other end being shaped to form a gripping means for the device which means lie in the common plane of the stem and the bent arms of the hook, the arm adjacent the stem being disposed at an obtuse angle slightly greater than a right angle to the stem, the outer arm being disposed at right angles to the stem, the angle between the arms of the V-shaped hook being within the range 7 to 20°, the inner radius of curvature at the elbow between the two arms being less than 0.032 inch, the arm remote from the stem of wire extending beyond the inner arm in the direction of the length of the arms.

15 5. A device for use in connection with the removal of an ordinary wire-wool pipe cleaner from a tobacco pipe which device consists of a length of substantially rigid wire of the minimum thickness equivalent to at least 0.032 inch, double cranked at one end to form a substantially V-shaped hook in the longitudinal plane of the main stem of wire, the angle between the arms of the V-shaped hook being 12°, the inner radius of curvature at the elbow between the two arms being less than 0.032 inch, the arm remote from the stem of wire extending beyond the inner arm in the direction of the length of the arms.

20 6. A device for use in connection with the removal of an ordinary wire-wool pipe cleaner from a tobacco pipe which device consists of a length of substantially rigid wire of a minimum thickness equivalent to at least 0.032 inch, double cranked at one end to form a substantially V-shaped hook in the longitudinal plane of the main stem of wire with the arm of said hook adjacent the stem bent on an arc outwardly 25 with a straight portion at an angle slightly greater than a right angle to the stem and bent back at an acute angle to the first arm to form an outer rectilinear arm extending beyond the inner arm and stem and in the same plane therewith, the other end being loop shaped to form a gripping means for the device which gripping means lie in the common plane of the stem and the V-shaped hook, the angle between the arms of the V-shaped hook being 12°, the inner radius of curvature at the elbow between the two arms

being less than 0.032 inch, the arm remote from the stem of wire extending beyond the inner arm in the direction of the length of the arms.

7. A device for use in connection with the removal of an ordinary wire-wool pipe cleaner from a tobacco pipe which device consists of a length of substantially rigid wire of a minimum thickness equivalent to at least 0.032 inch, double cranked at one end to form a substantially V-shaped hook in the longitudinal plane of the main stem of wire, the other end being shaped to form a gripping means for the device which gripping means lie in the common plane of the stem and the bent arms of the hook, the arm adjacent the stem being disposed at an angle other than a right angle to the stem, the outer arm being disposed at right angles to the stem, the angle between the arms of the V-shaped hook being 12°, the inner radius of curvature at the elbow between the two arms being less than 0.032 inch, the arm remote from the stem of wire extending beyond the inner arm in the direction of the length of the arms.

8. A device for use in connection with the removal of an ordinary wire-wool pipe cleaner from a tobacco pipe which device consists of a length of substantially rigid wire of a minimum thickness equivalent to at least 0.032 inch, double cranked at one end to form a substantially V-shaped hook in the longitudinal plane of the main stem of wire, the other end being shaped to form a gripping means for the device which gripping means lie in the common plane of the stem and the bent arms of the hook, the arm adjacent the stem being disposed at an angle other than a right angle to the stem, the outer arm being disposed at right angles to the stem, the angle between the arms of the V-shaped hook being within the range 7 to 20°, the inner radius of curvature at the elbow between the two arms being less than 0.032 inch, the arm remote from the stem of wire extending for a distance from 0.02 inch to 0.05 inch beyond the inner arm in the direction of the length of the arms.

9. A device for use in connection with the removal of an ordinary wire-wool pipe cleaner from a tobacco pipe which device consists of a length of substantially rigid wire of a minimum thickness equivalent to at least 0.032 inch, double cranked at one end to form a substantially V-shaped hook in the longitudinal plane of the main stem of wire, the other end being shaped to form a gripping means for the device which gripping means lie in the common plane of the stem and the bent arms of the hook, the arm adjacent the stem being disposed at an angle other than a right angle to the stem, the outer arm being disposed at right angles to the stem, the angle between the arms of the V-shaped hook being 12°, the inner radius of curvature at the elbow between the two arms being less than 0.032 inch, the arm remote from the stem of wire extending for a distance of from 0.02 inch to 0.05 inch beyond the inner arm in the direction of the length of the arms.

10. A device for use in connection with the

removal of an ordinary wire-wool pipe cleaner from a tobacco pipe which device consists of a length of substantially rigid wire of a minimum thickness equivalent to at least 0.032 inch, double cranked at one end to form a substantially V-shaped hook in the longitudinal plane of the main stem of wire with the arm adjacent the stem curvedly bent outwardly to form a straight portion substantially at an obtuse angle to the stem and then curvedly bent back at an acute angle to form a straight outer arm substantially at right angles to the stem and extending beyond the inner arm and stem to form a slight overhang, the angle between the divergent arms of the V-shaped hook being within the range of 7 to 20° to guide the pipe cleaner into the crotch formed thereby and the arms of the hook being in such close proximity as to tightly grip the cleaner transversely when applied thereto and the cleaner and hook are relatively canted by pulling the stem to remove the cleaner from the pipe, the inner radius of curvature at the elbow between the two arms being less than 0.032 inch, the arm remote from the stem of wire extending for a distance of from 0.02 inch to 0.05 inch beyond the inner arm in the direction of the length of the arms.

11. A device for use in connection with the removal of an ordinary wire-wool pipe cleaner from a tobacco pipe which device consists of a length of substantially rigid wire of the minimum thickness equivalent to at least 0.032 inch, double cranked at one end to form a substantially V-shaped hook in the longitudinal plane of the main stem of wire with the wire bent outwardly substantially at an obtuse angle and then bent in the reverse direction inwardly so that a line bisecting the angle therebetween is at right angles to the stem, the angle between the arms of the V-shaped hook being 12°, the inner radius of curvature at the elbow between the two arms being less than 0.032 inch, the arm remote from the stem of wire extending at least to the far side of the stem to freely hook under the end of such a pipe cleaner where it extends into the bowl of a pipe from the stem so as to bend and grip said cleaner when pulled outward.
